Assistant Examiner — Caleb M Baker

(57) **CLAIM**

The ornamental design for a charging case for smart ring as shown and described.

DESCRIPTION

FIG. 1 is a bottom, front and left side perspective view of a charging case for smart ring showing our new design; FIG. 2 is a top, rear and right side perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; FIG. 8 is a bottom plan view thereof; and, FIG. 9 is a bottom and left side perspective view showing the charging case for smart ring in an open state.

The broken lines in the drawings illustrate portions of the charging case for smart ring which form no part of the claimed design.
